CLAIM

The ornamental design for a cigarette pack display box, as shown and described.

DESCRIPTION

FIG. 1 is a top, front, and right side perspective view of a cigarette pack display box showing our new design;

FIG. 2 is a top plan view thereof;

FIG. 3 is a left side elevational view thereof;

FIG. 4 is a rear elevational view thereof; and,

FIG. 5 is a reduced top, front, and left side perspective view thereof.

The broken-line disclosure of indicia in all the views and the fragmentary view of a hand and cigarette packs in FIG. 5 are for illustrative purposes only and forms no part of the claimed design.
